CLAIM

The ornamental design for an activity apparatus, as shown and described.

DESCRIPTION

FIG. 1 is a top left front perspective view of an activity apparatus showing our new design;

FIG. 2 is a left side elevational view thereof;

FIG. 3 is a front elevational view thereof;

FIG. 4 is a right side elevational view thereof;

FIG. 5 is a rear elevational view thereof;

FIG. 6 is a top plan view thereof;

FIG. 7 is a bottom plan view thereof;

FIG. 8 is a top left front perspective view of the subject invention, shown with the environmental unclaimed features removed;

FIG. 9 is a left side elevational view of the subject invention, shown with the environmental unclaimed features removed;

FIG. 10 is a front elevational view of the subject invention, shown with the environmental unclaimed features removed; and,

FIG. 11 is top plan view of the subject invention, shown with the environmental unclaimed features removed.

The broken line showing of a net in FIGS. 1, 2, 3 and 6 is for illustrative purposes only and forms no part of the claimed design.
